INCLOSED ELECTRIC FUSE.

1,277,044.

Specification of Letters Patent. Patented Aug. 27, 1918.

Application filed March 28, 1918. Serial No. 225,177.

To all whom it may concern:

Be it known that I, ROBERT C. COLE, a citizen of the United States, residing at Hartford, in the county of Hartford and 5 State of Connecticut, have invented a new and useful Improvement in Inclosed Electric Fuses, of which the following is a specification.

This invention relates to the class of filled 10 fuses of the cartridge type, that is, those fuses which have insulating tubes with metal end caps, links of fusible metal with terminals extending through the end caps, and granular vapor-condensing and absorbing 15 material filling the interior about the links.

These fuses are safety devices and are made to operate accurately, consequently it is considered very desirable that they be 20 constructed so that they cannot be refilled by everybody after they have been blown, and thus eliminate the possibility of the insertion of links of non-fusible wire or of fusible wire that is of greater capacity than 25 the rating of the fuses or is safe for the circuits in which the fuses are to be used, by an unskilled person, which would render the fuses elements of danger rather than safety devices. It is, however, sometimes advan- 30 tageous to have these fuses constructed so that while they cannot be readily refilled by unskilled persons they may be refilled by the manufacturer in order that all of the parts of a large quantity of blown fuses may 35 not have to be thrown away. It is necessary in order to attain accuracy that not only the fuse links be of correct carrying capacity, but that their terminals be solidly joined to the end caps, and furthermore it is necessary 40 that the end caps be securely attached to the insulating tubes so that they will not be blown off by the pressure of the gas generated when the fuses are blown and the metal of the links changes from a solid to a 45 vaporous state.

The object of this invention is to provide what may be termed a semi-refillable fuse, that is, a fuse of this nature which, while not readily refillable by the ordinary individual, can be cheaply refilled by the manufacturer.

This object is attained by securing the metallic end caps to the ends of the insulating tube so that they cannot be taken off and 55 forming these end caps in a way that en-

ables the granular material to be easily filled into the tube and the terminals of the fusible link and of an indicator wire, if used, to be quickly located and easily soldered to the caps in such manner that when it is desired to refill the tube after the link has been blown the end caps can be opened and a new link, a proper indicator wire and fresh filling material can be substituted without destroying any of the formed parts. 65

Figure 1 of the accompanying drawing is a view on enlarged scale of a fuse embodying this invention showing it in condition to be filled. Fig. 2 is a similar view showing the fuse filled and the terminals of the 70 fusible link soldered to the end caps. Fig. 3 shows a plan of an end cap that may be used. Fig. 4 shows a side view of the end cap.

The case 1 of the fuse is desirably made of 75 a tube of insulating fiber. The metal caps 2 are fitted over the ends of the tube and the edges 3 of the caps are crimped into the body of the tube so that the caps cannot be removed after having once been fixed in 80 place. These caps have perforated reëntrant outer ends, that is, their ends are provided with inwardly extending cup-shaped recesses 4 with openings 5 of substantial size through the bottom of the cups. The fusible 85 link may be made in the ordinary way of the usual material. This link is shown in the drawings as extending through the tube and as having its terminals passing through the openings into the cups in the end caps. 90 Thin metallic cup-shaped plates 7 are set in the openings in the bottoms of the cup-shaped recesses in the end caps. These cups are perforated with openings that just fit the terminals of the link. Before the plates 95 are placed in position the case is filled with granular insulating material 8 for condensing and absorbing the gases generated by the melting of the link when the fuse is blown. After the plates have been inserted 100 in the recesses in the end caps with the terminals of the link extending through them, the recesses are filled flush with solder 9 and the ends smoothed off so that the ends will be flat to form a desirable finish and 105 also enable them to make proper contact with the terminals of a plug when it is desired to use the fuse therein. The melted solder is easily flowed into the recesses in the end caps and it secures the plates in place 110

and makes a firm and substantial metallic joint and close electrical connection between the link terminals and the end caps.

The metallic cap may have small tongues 5 10 struck outward from the material of its ends to form a cleat about which the end of a fine indicating wire, if used, may be rove to retain it until the link and cap are soldered, and a notch 11 may be made in the 10 15 edge of the opening through the cap for the passage of such indicating wire.

The end caps are first placed upon and 15 permanently secured to the tube and one end closed with the link terminal, plate and 20 cap soldered together. The filling material is then inserted through the opening in the other end cap and after the tube is filled 25 the plate is placed in this cap at this end and the solder poured in. This fuse is not readily renewed by the ordinary individual, but the manufacturer receiving a large number 30 of blown fuses, may simply melt the solder from the recesses in the end caps and knock out the plates when thus freed. The mains of the melted fuse link and the filling material may then be shaken out through the openings in the end caps. After the tubes have been cleaned in this way a new link may be inserted, fresh filling may be 35 poured in and the end caps again closed by

inserting the plates and resoldering them in place.

The invention claimed is;

1. An inclosed electric fuse comprising an insulating tubular case, metallic caps permanently fastened on the ends of the case, 35 said caps having reëntrant perforated outer ends, perforated metallic plates located in the bottom of the recesses in said caps, a fusible link with terminals extending 40 through the perforations in said plates, granular absorbing and condensing material filling the case, and solder filling the recesses in the end caps and mechanically and 45 electrically uniting the link terminals, plates and caps.

2. An inclosed electric fuse comprising an insulating tubular case, metallic caps permanently fastened on the end of the case, 50 said caps having reëntrant perforated outer ends and portions of their ends struck out to form a cleat, perforated metallic plates located in the bottom of the recesses in said caps, a fusible link with terminals 55 extending through the perforations in said plates, and solder filling the recesses in the end caps and mechanically and electrically uniting the link terminals, plates and caps.

ROBERT C. COLE.
